UNITED STATES PATENT OFFICE.

CARL B. PARSONS, OF DETROIT, MICHIGAN, ASSIGNOR TO PARSONS MANUFACTURING COMPANY, OF DETROIT, MICHIGAN.

HINGE.

Application filed September 8, 1921. Serial No. 499,181.

To all whom it may concern:

Be it known that I, CARL B. PARSONS, citizen of the United States, residing at Detroit, county of Wayne, State of Michigan, have invented a certain new and useful Improvement in Hinges, and declare the following to be a full, clear, and exact description of the same, such as will enable others skilled in the art to which it pertains to make and use the same, reference being had to the accompanying drawings, which form a part of this specification.

My invention relates to improvements in hinges. An object is to provide a hinge for outdoor use, such as the hinge used in connection with an automobile body door, so constructed that the exposed part of the hinge, and particularly the joint, will be protected from the weather, thereby preventing rust and corrosion of the hinge metal and especially the joint.

A further object is to provide a hinge of such a character so constructed that the opening of the hinge will be limited to less than 180 degrees, for example, approximately 90 degrees, therefore protecting the side of the car body from mutilation by the swinging door.

A further object is to provide in connection with the complementary hinged sections pivoted together to comprise a hinge, a supplemental cover-plate for one of said hinge sections turned over at one end to embrace the hinge joint and overlapping said hinge sections at the joint on one side at least; said cover-plate may likewise be so constructed as to limit the outward swinging movement of the hinge sections about their pivot at such point as may be desired. Such cover-plates serve to give the hinge a neat, clean cut appearance as of a unitary structure without any exposed working parts.

These and other objects, together with details of construction, will more fully appear from the following description, appended claims and accompanying drawing, in which:

Figure 1 is an elevation of my improved hinge.

Fig. 2 is an end view of the hinge shown in Fig. 1.

Fig. 3 is a plan view of one type of hinge construction.

Fig. 4 is a horizontal section taken on the line 4—4, Fig. 2.

Fig. 5 is a plan view showing another form of the hinge in the closed position.

Fig. 6 is a horizontal section of the form of hinge shown in Fig. 5.

In the manufacture of hinges, it is old to construct a cast iron hinge in which one of the hinge sections is formed with a transverse concavity at one end within which is pivoted the end of the complementary hinged section, thereby protecting to a degree the hinge from the weather.

In my invention, I have devised a supplemental cover-plate for use in connection with the conventional type of hinge, which cover-plate may be made of a stamping and is not only adapted to serve as a cover for one of the hinge sections and to enclose the hinge joint, but is also adapted to limit the outward swinging movement of the hinge when it is opened.

My hinge comprises complementary hinge sections *a* and *b* pivoted together at one end by means of a pivot pin *c*. These hinge sections may be straight as shown in Figs. 5 and 6, or curved as shown in Figs. 3 and 4. The hinge sections are perforated as at *d* to provide apertures thru which fastening screws or nails may be passed to fasten the hinge in place to the door and door jamb.

I provide a coverplate *e* which forms a complementary member for one of the hinge sections and is turned over at the end as at *f* partially embracing the hinge joint as shown in the several figures of the drawing, particularly Figs. 2, 4 and 6. The cover plate is likewise turned as at *g* on one side at least, to form a flange adapted to overlap the hinge sections at the joint and adjacent the hinge joint, as shown in Figs. 2, 3 and 5.

As shown in the several figures of the drawing, the cover plate is turned over on each side forming opposed side flanges which overlap the two hinge sections, as shown in Figs. 3 and 5 when the hinge is closed, not only overlapping the hinge sections at the joint, but adjacent the joint, so as to protect the exposed portion of said hinge sections when the hinge is in place. However, though the cover-plate is shown as turned over on each side forming two protective side flanges, it is apparent that

the purpose might well be served if it were merely turned over on one side, such side being used as the top of the hinge when in place, the bottom of the hinge being left 5 uncovered.

Not only does my cover plate serve to protect the hinge at the joint from the action of the weather by embracing the pivoted ends of the hinge sections, and provide a 10 hinge having a finished, clean appearance, but the turned over end of the plate at the joint serves as a stop to limit the outward swinging movement of one of the hinge sections, relative the other, when the hinge is 15 opened, limiting the opening to less than 180 degrees, as here shown the opening of the hinge would approximate 90 degrees.

This feature of limiting the outward swinging movement of the hinge sections 20 relative each other proves particularly useful in automobile construction where these hinges are used to mount automobile doors and during the movement of the car through the shop, from one shop operation to another, prior to the time the check straps are 25 placed on the doors to limit the outward swinging movement thereof, the doors frequently accidentally swing open and unless there is some means of limiting the open- 30 ings, strikes the side of the vehicle body, in many instances marring or mutilating the

same. My form of hinge prevents the occurrence of such accidents.

What I claim is:

1. In a hinge having a pair of hinge members provided with interengaging knuckles connected together by a pivot pin, a cover plate channelled to receive one of said hinge members, which channel is provided at the outer end with a hood which 35 encloses the hinge joint.

2. In a hinge having a pair of hinge members pivoted together at one end, an independent cover plate channelled to receive both hinge members when folded together, 40 which channel is closed at the outer end forming a pocket which substantially encloses the hinge joint.

3. In a hinge comprising a pair of hinge members pivoted together at one end, a 45 cover plate secured to one of said members having a hood at the outer end to enclose the hinge joint.

4. In a hinge comprising a pair of hinge members pivoted together, a channel cover plate carried by one of said members, the 50 channel of which is closed at the outer end to form a pocket which encloses the hinge joint.

In testimony whereof I sign this specification.

CARL B. PARSONS.
